SEWING MACHINE SHUTTLE

Alfred R. Wood, Bridgeport, Conn., assignor to
The Singer Manufacturing Company, Elizabeth, N. J., a corporation of New Jersey

Application January 2, 1937, Serial No. 118,845

2 Claims. (Cl. 112—232)

This invention relates to sewing machine shuttles, more particularly of the type comprising a circularly moving shuttle-body having an arbor on which a stationary cup-shaped bobbin-thread-case is journaled. A metallic bobbin wound with thread is customarily received within the thread-case, which latter commonly has a tubular central member constituting a bearing for the thread-case upon the arbor of the shuttle-body and further constituting an arbor for the bobbin.

Thread manufacturers furnish sewing machine users with wound cops of thread on paper spools of approximately the same size and shape as the metallic bobbin in lieu of which they are designed to be used. These factory wound cops, however, have a tendency to swell or shrink, depending upon atmospheric conditions, and hence must be manufactured within such size limits that under no condition will they bind or drag in the sewing machine thread-case but will under all conditions be free to unwind within the thread-case. As a result of this requirement, the wound paper spool or cop usually fits the thread-case more freely or with more play than the metallic bobbin, but in neither case is it practicable to fit the rims of the bobbin flanges so closely within the inner cylindrical wall of the thread-case that the bobbin-thread cannot at times escape therebetween.

When a lock-stitch sewing machine is operated at high speeds, the bobbin-thread is subjected to a rapid succession of jerks which frequently causes the bobbin to overrun and "spill" the bobbin-thread within the thread-case. When bobbin-thread is spilled within the thread-case it frequently escapes or "leaks" out of the thread-case and is fouled, caught, kinked or broken by parts of the machine. Much experimenting has been done and many devices have been made to prevent spilling of bobbin-thread within the thread-case and subsequent leakage of spilled thread therefrom. Such devices commonly comprise some sort of spring washer or friction means to be housed with the bobbin or cop within the bobbin-case for the purpose of placing a frictional drag upon such bobbin or cop. These devices have not been successful for various reasons, chiefly because they impose a variable tension upon the bobbin-thread depending upon the amount of thread on the bobbin. The tension caused by this drag is least with a full bobbin and increases as the bobbin unwinds, becoming a maximum when the bobbin is practically exhausted. Uniform sewing cannot be done under such conditions.

The present invention aims to provide an im-

proved sewing machine shuttle from which the bobbin-thread cannot escape under any condition and with which uniformly satisfactory sewing may be done using either wound metallic bobbins or paper clad cops.

With the above and other objects in view, as will hereinafter appear, the invention comprises the devices, combinations, and arrangements of parts hereinafter set forth and illustrated in the accompanying drawing of a preferred embodiment of the invention, from which the several features of the invention and the advantages attained thereby will be readily understood by those skilled in the art.

According to the present improvement no attempt is made to prevent "spilling" of bobbin-thread within the thread-case, but means are provided to effectively prevent escape of the spilled thread from the thread-case.

The invention will be more fully understood by reference to the accompanying drawing, of which Fig. 1 is a front face elevation of a sewing machine shuttle embodying the invention. Fig. 2 is a rear face view of the shuttle. Fig. 3 is an enlarged section on the line 3—3, Fig. 1. Fig. 4 is a perspective view of the shuttle body from which the thread-case has been removed. Fig. 5 is a disassembled perspective view of the thread-case and cop, and Fig. 6 is a fragmentary sectional view similar to Fig. 3 but on a still further enlarged scale.

The shuttle body A of the circularly moving oscillatory type is formed as usual with a semi-circular bearing rib 1 terminating at one end in a loop-taking beak 2. The shuttle body A is further formed with a rear wall 3 which supports the arbor 4 on which the stationary cup-shaped thread-case B is journaled.

The cup-shaped thread-case B has at its open end a circular rim 5 and an internal tubular bearing element 6 coaxial with the rim 5 and freely journaled on the arbor 4. The thread-case is adapted to receive the usual bobbin-thread spool or cop 7 which must be of a size such that it will not drag appreciably upon the thread-case or its bearing element 6 as the bobbin-thread 8 is being used.

The bobbin-thread 8 is drawn through the threading slot 9 and under the usual tension-spring 10 from which it leads upwardly through the guide hole 11 in the rotation-restraining arm 12 to the work. In practice, the rotation-restraining arm 12 on the thread-case B is loosely engaged at its upper end by a notched rotation-restrain-

ing element (not shown) fixed on the sewing machine frame.

The thread-case B has the usual spring-pressed latch slide 13 which engages the shoulder 14 in 5 the arbor 4. The latch slide 13 has hinged to it at 15 a finger-operated lever 16 formed at one end with a short arm 16' which, when the lever 16 is swung about the hinge 15 bears upon the fixed corner 17 of the thread-case and effects re- 10 traction of the latch-slide from engagement with the shoulder 14, thus unlocking the thread-case for removal from the arbor 4. The finger-operated lever 16 has an upturned free terminal portion 16^a by which it is readily engaged and 15 opened by the operator. The broadly curved free edge 16^b at the terminal portion of the lever 16 permits the free and easy passage of the cast needle-loop thereover as the needle loop is being drawn up in the usual manner by the sewing ma- 20 chine take-up (not shown).

The shuttle-body A is formed in the inner face of its rear wall 3 with a completely circular groove 18 the diameter a of which is approximately equal to that of the rim 5 of the thread-case in 25 juxtaposition thereto. Preferably, the rim 5 is smoothly rounded in cross-section and received in the groove 18; being clear of the walls of the latter. This construction provides a tortuous or bent clearance gap, Fig. 6, between the groove 18 30 and rim 5 which forms an effective seal against escape or leakage of spilled bobbin-thread, without subjecting the parts to frictional wear or re-

quiring extreme accuracy in their manufacture. Any thread spilled within the thread-case will be used up in regular course without danger of being fouled, caught or broken by moving parts outside of the thread-case, or of being wedged between the thread-case and shuttle-body and damaged in consequence thereof. 5

Having thus set forth the nature of the invention, what I claim herein is:—

1. In a sewing machine, the combination with 10 a stationary cup-shaped bobbin-case having at its open end a circular rim and having within it a tubular bearing element coaxial with said rim, of a circularly moving shuttle-body having an arbor on which said bearing element is freely 15 journaled and a rear wall which carries said arbor and is formed in its inner face with a completely circular groove of substantially the same diameter as the rim of the thread-case and in juxtaposition with said rim.

2. In a sewing machine, the combination with 20 a stationary cup-shaped bobbin-case having at its open end a circular rim and having within it a tubular bearing element coaxial with said rim, of a circularly moving shuttle-body having 25 an arbor on which said bearing element is freely journaled and a rear wall which substantially closes the open end of said bobbin-case, there being a tortuous clearance gap between said rear wall and the rim of said bobbin-case. 30
